UNITED STATES PATENT OFFICE.

GEORGES CLAUDE, OF PARIS, FRANCE.

BLOWPIPE.

No. 882,887.

Specification of Letters Patent. Patented March 24, 1908.

Application filed December 27, 1906. Serial No. 349,737.

To all whom it may concern:

Be it known that ¹GEORGES CLAUDE, a citizen of the Republic of France, and resident of 43 Rue St. Lazare, Paris, France, 5 have invented Improvements in Blowpipes, of which the following is a specification.

As is known at the present time there is no difficulty in effecting the autogenous soldering of the refractory metals and especially of 10 iron and its derivatives by means of the oxy-acetylenic or oxhydric blow pipe. On the other hand if the acetylene or the hydrogen are replaced by illuminating gas it is generally difficult to solder iron. The process 15 which forms the object of the present invention permits of overcoming this difficulty.

It consists in raising the temperature of the flame by heating the mixture of oxygen and combustible gas before the ignition. It 20 has been found to be possible notwithstanding the presence of the oxygen to heat it some hundreds of degrees without causing its premature and explosive combustion. The mixture may be subjected for example during 25 its passage through the tube conducting it to the nozzle, to the action of a row of gas jets supplied by an appropriately regulated branch pipe from the blow-pipe supply, the temperature of the flame is noticeably raised; 30 the incandescence and then the fusion of the pieces of metal being treated are considerably accelerated; further, the preliminary heating of the gaseous mixture permits of producing between the oxygen and the combustible gas an intimate and perfect mixture 35 whereby it becomes possible to obtain conditions favorable to efficient soldering. This favorable circumstance which has great technical importance cannot be attained by heating 40 the oxygen and the combustible gas separately; the latter may be previously subjected to a slight pressure which facilitates the mixture and the velocities of flow. In place of a preliminary compression of the 45 gas, any insufficiency in its pressure may be remedied by displacing it by the compressed oxygen acting on the principle of the Giffard injector. If necessary, the mixture of the gases may take place before they enter the 50 blow-pipe. This raising of the temperatures may also be employed in the case of oxhydric or other blow-pipes with a view of increasing the rapidity of their action or of obtaining effects of which they would otherwise be in-

capable; further, water gas, petroleum vapor and similar combustibles may be employed in the place of illuminating gas.

Figure 1 illustrates a section through a blow-pipe and shows by way of example a method of carrying the principle of the invention into practice. The oxygen enters this blow-pipe through the tube A, which is prolonged into the hollow handle P by the tube E. This tube ends in a conical tube F and the centering washer M provided with holes N provides for its support. The combustible gas enters through the tube B provided with a cock C and traverses the chamber D concentric with E; it then passes through the holes N after which it is carried along by the current of oxygen which issuing from F with a high velocity acts in the manner of a Giffard injector and carries the combustible gas along. In the part G which presents a restriction the gases owing to the diminution of the cross-section for their flow acquire a high velocity which enables them to mix. The mixture then traverses the tube H and the chamber I at the upper part of which a hole K is formed; the gaseous mixture issuing at K is kindled and the flame thus produced permits of heating the different convolutions of the serpentine coil L and consequently the mixture of gases which traverses this coil on leaving the chamber I; this arrangement permits of raising the temperature of the mixture of the combustible and conburent gases before they are kindled on issuing from the nozzle R. This preliminary heating of the gaseous mixture renders it possible to obtain technical effects for the soldering which it is impossible to secure with ordinary blow-pipes in which illuminating gas, water, gas, petroleum essences, or the like are utilized as combustible gases. Finally another technical effect which the raising of the temperature renders it possible to obtain may be pointed out. It is known that when a piece of iron has been heated to a white red, a jet of oxygen sent on to its surface provokes a combustion thereon the iron burning with such intensity that the metal fuses rapidly beneath the jet, and it is possible to cast, cut, or perforate pieces of metal of very large size. If, for example, the initial increase of temperature of the metal has been obtained by an oxhydric or an oxy-acetylenic blow-pipe, it is only neces-

sary to cut off the supply of the combustible gas as soon as the heating has been effected, and allow the oxygen alone to act. Under these conditions however, the success of the operation is a little difficult to insure; if the part raised preliminarily to a white heat is not somewhat extensive, a moment of inattention or a momentary uncertainty in the direction of the jet will be sufficient to cause the reaction to cease and the mass to cool rapidly. Now it has been found that the application to oxygen of the preliminary heating by means of a portion of the mixture furnishes excellent results in this case as a matter of fact if the oxygen of the jet is heated this way the reaction is largely facilitated, and the operation proceeds exceedingly easily. In order to avoid the difficulty of eliciting the ignition by heating the oxygen before the oxygen and the oxygen of the jet are mixed, a device is used which consists of a tube having a narrow neck at the top, and a wider lower portion. The oxygen of the jet is introduced into the narrow neck, and the oxygen of the mixture is introduced into the wider lower portion. The oxygen of the jet is heated by the oxygen of the mixture, and the reaction is set in motion.

Having described my invention I claim—
In a blow pipe adapted for using a mixture
of oxygen and a combustible gas, a mixing
chamber, a main burner connected therewith
by a coiled tube and a supplemental burner
connected with said mixing chamber and
located in proximity to said tube, said last
named burner being adapted to utilize a por-
tion of the gaseous mixture in heating the
gases passing through said coiled tube, sub-
stantially as described. 20 25

In testimony whereof I affix my signature 30
in presence of the witnesses.

GEORGES CLAUDE
